UNITED STATES PATENT OFFICE.

OLIVER E. PONTIOUS, OF WAUSEON, OHIO.

WRENCH.

SPECIFICATION forming part of Letters Patent No. 681,260, dated August 27, 1901.

Application filed April 22, 1901. Serial No. 56,904. (No model.)

To all whom it may concern:

Be it known that I, OLIVER E. PONTIOUS, a citizen of the United States, residing at Wauseon, in the county of Fulton and State of 5 Ohio, have invented new and useful Improvements in Wrenches, of which the following is a specification.

This invention relates to wrenches; and the main object in view is to provide a simple and 10 convenient form of quick-acting wrench by means of which the movable or adjustable jaw of the wrench may be quickly shifted any desired distance along the handle or stock of the implement, so as to bring said movable 15 jaw into close relation to a nut, pipe, or other article to be grasped and held between the wrench-jaws, after which the movable jaw may be adjusted into actual contact with or 20 close relation to such nut or article and its movement away from the same prevented during the operation of turning a nut or other article.

The specific object of the invention is to provide, in connection with the movable jaw 25 and feed or adjusting screw, a forked thumb-piece which forms a connection between the adjusting-screw and movable jaw and which also embraces the handle of the wrench and lies in position to be conveniently grasped 30 and operated by the thumb and forefinger of the operator's hand.

With the above and other objects in view the invention consists in the novel construction, combination, and arrangement of parts 35 hereinafter fully described, illustrated, and claimed.

In the accompanying drawings, Figure 1 is a side elevation of a wrench constructed in accordance with the present invention. Fig. 40 2 is an edge view of the same, and Fig. 3 is a detail perspective view of the forked thumb-piece.

Similar numerals of reference designate corresponding parts in all figures of the drawings.

45 Referring to the drawings, 1 designates the handle or stock of the wrench, which is shown as of rectangular shape in cross-section and provided at one end with a fixed or immovable jaw 2.

50 In carrying out the present invention a movable or adjustable jaw 3, which embraces

the handle 1 and is slidably mounted thereon for movement toward and away from the fixed jaw, has pivotally connected thereto a forked thumb-piece 4, which is provided with 55 a lug or ear 5, which fits in a socket 6 in the movable jaw 3 and is held pivotally therein by means of a pivot-pin 7. The thumb-piece 4 is provided with fork-arms 8, which extend transversely of the handle 1 and on opposite 60 sides thereof, said fork-arms serving to guide the thumb-piece as it is vibrated toward or away from the handle and also forming finger-grips, so that the operator may grasp said fork-arms between his thumb and forefinger 65 for the purpose of disengaging the feed or adjusting screw in order to slide the movable jaw quickly along the wrench-handle. The forked thumb-piece is further provided with a recess 9, in which is received one end of 70 the adjusting or feed screw 10, the threads of which are adapted to engage teeth or threads 11 in the rear edge of the handle 1, as clearly illustrated in Figs. 1 and 2. The screw 10 is rotatably mounted on a pin 11^a, 75 which is screwed into a threaded opening in the forked thumb-piece 4 and held. The pin 11^a may, however, be fastened to the forked thumb-piece in any preferred way. When the thumb-piece is rocked outward or away 80 from the handle 1, the adjusting-screw 10, which is carried by the thumb-piece, is also rocked outward and moved out of engagement with the teeth or threads 11 on the handle. The screw 10 is normally held in engagement with the handle by means of a pressure-spring 12, one end of which is connected to the movable jaw 3 and the opposite or free 85 end of which bears against the forked thumb-piece 4. 90

It will be seen that the operator by grasping the forked thumb-piece 4 may rock the adjusting or feed screw 10 out of engagement with the handle 1 and then quickly slide the movable jaw toward or away from the fixed 95 jaw, so as to bring both jaws into close relationship to the nut or other object to be clamped. The spring then restores the adjusting-screw to its normal position, after which the operator by turning said screw 100 may effect a nice adjustment of the parts prior to turning the nut on or off.

Having thus described the invention, what I claim as new, and desire to secure by Letters Patent, is—

A wrench comprising a handle; a fixed jaw thereon; a movable jaw slidably mounted thereon; a spring-pressed thumb-piece pivotally connected to the sliding jaw and provided with fork-arms which embrace the wrench-handle; and an adjusting-screw car-

ried by the forked thumb-piece and having a swivel engagement therewith and a threaded engagement with the handle of the wrench.

In testimony whereof I affix my signature in presence of two witnesses.

OLIVER E. PONTIOUS.
